COMBINED TOY BUCKET, SHOVEL, FUNNEL, AND STRAINER

Sidney A. Tarrson, 518 S. Racine,
Chicago, Ill. 60607

Filed Feb. 23, 1967, Ser. No. 5,914

Term of patent 14 years

(Cl. D34—15)

FIG. 1 is a front perspective view of a combined toy bucket, shovel, funnel, and strainer showing my new design;

FIG. 2 is a side elevational view thereof;

FIG. 3 is a top plan view thereof;

FIG. 4 is a bottom plan view thereof.

I claim:

The ornamental design for a combined toy bucket, shovel, funnel, and strainer, as shown.
